UNITED STATES PATENT OFFICE

JOHAN VIKTOR BLOMQUIST, OF STOCKHOLM, SWEDEN, ASSIGNOR TO AKTIEBLAGET ATMOS, OF STOCKHOLM, SWEDEN, A CORPORATION OF SWEDEN, AND SOCIETE ALSACIENNE DE CONSTRUCTIONS MECANIQUES, OF MULHOUSE, FRANCE, A CORPORATION OF FRANCE

ROTATING STEAM BOILER

Application filed November 24, 1930, Serial No. 497,866, and in Germany December 18, 1929.

The U. S. patent application Ser. No. 252,332, filed Feb. 6th, 1928, describes a slowly rotating steam boiler, in which the generation of the steam takes place within a plurality of straight-lined tubes rotatably mounted around a central container communicating with said tubes, and for the purpose of preventing the water from being driven completely out from the tubes, when the latter move above the water level in the central container during the rotation, the tubes are connected with the container by pipes which are throttled one way or the other, or provided with overflow inlets or similar means.

According to the construction of the steam generators of this type as hitherto employed, the firing must be performed beneath the rotor member formed by the aforesaid steam generating tubes and central container, and therefore the generator plant requires a fireplace surrounded by brickwork. As this brickwork will be subjected to the radiant heat from the fire, it will rather easily be damaged.

According to the present invention this inconvenience is eliminated, in that the central container in its direction of length is made so short that it will be sufficient to support the same at its one end only. Thereby the bearing means at the opposite end may be dispensed with, and the steam generating tubes at this end supported by an annular end plate preferably resting on rolls and forming a central aperture for feeding in the fuel, either in powder form or otherwise, into the interior of the squirrel-cage shaped rotor structure formed by the steam generating tubes together with the end members of the boiler. Consequently, the interior of the rotor structure will form the fireplace in the steam boiler, and in a construction of this kind the brickwork forming part of the plant will not be directly subjected to the radiant heat from the fire. Therefore the air needed for the combustion may also be pre-heated in a very high degree, which circumstance involves a very great advantage as far as the firing of steam boilers is concerned, as well known to those skilled in the art.

When using fuel in the shape of lumps or pieces, the steam generating tubes may be provided with reinforcements in such a manner that no special grate construction is required, in that the tubes form themselves the grate needed for the firing.

The invention is illustrated in the accompanying diagrammatical drawings, wherein

Fig. 1 shows an embodiment of the invention in longitudinal section, and

Fig. 2 shows a cross section of the same seen in the direction of the fuel feed end.

Figs. 3 and 4 in the same manner as Fig. 2 show two different modifications of the grate construction, and

Fig. 5 is a longitudinal section of the boiler corresponding to Fig. 4.

According to Fig. 1, the feed water, from a pre-heater of any suitable kind (not shown), is introduced into the pipe 1 and to the hollow pivot 2 for delivery into the chamber 3, from where the water by means of the communication pipes 4 is distributed in the steam generating tubes 5 mounted around a common horizontal, or slightly inclining, axis of rotation, whereby the tubes may be positioned parallel to this axis or in a formation tapering towards one end of the boiler.

At their one end, the tubes 5 are supported in bores, or other apertures, in an end plate 6 which is annular and provided with a central aperture 7, by means of which the fuel is fed in into fire place 8 formed within the squirrel-cage shaped rotor construction. The plate 6 is provided with a central end boss 85 surrounding the aperture 7 and forming a pivot for the rotor at this end, the said boss being provided with a bearing race 11 resting on two or more rolls 10.

At its other end the complete rotor construction is supported by a bearing 9, which according to the drawings is supposed to be a combined supporting and thrust bearing.

During the steam generation, the rotor structure is kept in a slow continuous rotation, for instance by means of a belt pulley 18, so that the water at hand in the central container 20, connected with the steam generating tubes by means of the overflow pipes 21 for permitting the escape of the steam,

does not take part in the rotation and is not subjected to any substantial centrifugal action but will maintain its free level in a substantial horizontal position.

5 When using a fuel in the shape of lumps or pieces, the fuel is fed in by means of a feed worm conveyor or the like (not shown) from a hopper 12 into the fire place. In order in such case to give the tubes 5 a sufficient 10 strength for supporting the fuel, they are exteriorly interconnected by means of a number of iron straps 13 positioned in a suitable interspaced relation. On account of the 15 rotating movement, the fuel is automatically distributed and caused to cover the lower tubes along their whole length. The air needed for the combustion is transmitted to the fuel through the interspaces between the tubes 5, and the combustion gases escape 20 through the interspaces between the tubes not covered by the fuel.

Another construction for reinforcement of the tubes 5 is shown in Fig. 3. According to this figure, the tubes 5 are interconnected substantially to their whole length by means of longitudinal bars 14 secured by means, for instance, of welding, and provided with holes 15 distributed along the length of the bars and serving for admittance of the combustion 30 air and escape of the combustion gases in a manner easily to be understood without specific explanation.

If the tubes 5 are surrounded by iron straps 13 as described above, a rather substantial 35 leakage or free space will be at hand between the tubes and the brickwork in the places adjacent to the brick work between the iron straps, and thereby a portion of the air will unnecessarily pass by the rotor structure and cool the combustion gases. In order 40 to reduce this leakage to a minimum, the tubes 5 may be provided with longitudinal and outwardly extending flanges 16 as indicated in Figs. 4 and 5. Hereby the iron 45 straps 13 are suitably provided with recesses 17 in which the ends of the flange pieces 16 are inserted, so that one or both ends of the latter is freely supported by the iron straps 13.

50 To those skilled in the art, it will be apparent that a temperature as high as up to 500° C. on the combustion air is permissible without risks for damages to the generator or the brickwork.

55 What I claim and desire to secure by Letters Patent is:—

1. In a slowly rotating steam boiler, a rotor construction consisting of a plurality of interspaced steam generating tubes 60 mounted around and communicating with a central container positioned substantially at one end of the boiler, means adapted for preventing a complete return of the water from the generating tubes to the central container through the communication means posi-

tioned therebetween, an end plate positioned at the opposite end of the boiler and forming a support for the steam generating tubes at that end, and a central opening in said end plate adapted for introduction of fuel into 70 the interior of the squirrel-cage shaped rotor structure formed by the steam generating tubes and the end members of the boiler.

2. In a slowly rotating steam boiler according to claim 1, the additional feature that 75 the end plate provided with the central opening is connected with a tubular boss serving as a pivot for the boiler at the adjacent end thereof.

3. In a slowly rotating steam boiler according to claim 1, the additional feature that 80 the steam generating tubes are interconnected by reinforcement means forming openings for the passage of air and gases through the interspace between the tubes.

85 In testimony whereof I have signed my name to this specification.

JOHAN VIKTOR BLOMQUIST.
